ATTORNEY.

UNITED STATES PATENT OFFICE.

GEORGE F. GODLEY, OF PHILADELPHIA, PENNSYLVANIA.

LUBRICATOR.

No. 891,928.

Specification of Letters Patent.

Patented June 30, 1908.

Application filed October 12, 1907. Serial No. 397,059.

To all whom it may concern:

Be it known that I, GEORGE F. GODLEY, a citizen of the United States, and a resident of Philadelphia, in the county of Philadelphia and State of Pennsylvania, have invented certain new and useful Improvements in Lubricators, of which the following is a specification.

This invention relates to certain improvements in car axle and other bearing lubricators, in which there is a sufficient amount of vibration to cause the piston to pump the lubricant to the bearing.

The principal object of the present invention is to provide simple, durable, reliable and efficient means whereby the lubricant is pumped from the reservoir below the axle to the surface of the axle or other bearing to be lubricated.

Another object is to provide a cushioned plunger for the lubricator, carried by the journal plate thereof and adapted to be operated by the impact of the journal.

Another object is to provide means for retaining the lubricator as a whole in proper position with respect to the journal and axle box.

Other objects will appear hereinafter.

The invention consists of the improvements hereinafter described and finally claimed.

The nature, characteristic features and scope of the invention will be more fully understood from the following description taken in connection with the accompanying drawings forming part hereof, and in which

Figure 1, is a longitudinal sectional view of a car axle box, illustrating the lubricator of the invention in application thereto. Fig. 2, is a transverse sectional view drawn to an enlarged scale of the lubricator embodying the invention. Fig. 3, is a plan view illustrating the journal plate. Fig. 4, is a fragmentary view in plan of the valve seat, and Fig. 5, is a perspective view of means for retaining the lubricator in proper position with respect to the journal and axle box.

Referring to the drawings *a*, is the axle box, *b*, is the journal, and *c*, is the bearing, all of well-known construction. Resting upon the bottom of the axle box is a frame *d*, having a tubular projection *e*. Within the tubular projection is a member *f*, provided with a valve seat adapted to receive a valve. As shown in the drawings, this member *f*, comprises a member that is separate from the

frame *d*, and is shown as being forced within the off-set *d*, of the frame *d*.

g, is the discharging valve, which in the present instance is a ball, although other forms of valves may be used to advantage, and is shown as being adapted to normally seat itself with respect to the valve seat *f*, of the member *f*. This member *f*, is provided with a number of vertically arranged members *h*, shown as being formed integral with the member *f*, and arranged radially of the valve seat *f*, and having spaces between them. These members *h*, serve to prevent the valve from rolling around, or in other words, serve to limit the movement of the valve to an up and down or vertical movement. The member *f*, constitutes, as it were, the floor of the tubular projection *e*, and this floor is shown as sloping toward the valve seat *f*, in order that sediment may find its way through the valve opening. By this construction, sediment which may accumulate in the lubricator interior may readily pass from the device between the spaces between the members *h* to and through the valve opening *f* to the journal box interior.

m, is a plate curved to fit the under side of the journal, and is provided with a flange or sleeve *n*, extending downwardly within the tubular projection *e*, and provided upon its interior walls, and at or near the bottom thereof with pins or other convenient projections *o*, for a purpose to be presently described. Surrounding the upper edge of the plate is a bearing rib *m*, having slots or openings at its corners, this rib forms a pocket for the lubricant. Extending rearwardly and of the same thickness as the rib is what may be termed a wiper *m*, which is adapted to wipe off oil that has the tendency to run back from the journal to the axle. This plate *m*, is provided with extensions *p*, as is the frame *d*, and the two extensions are connected together by a link connection *p*, in order to hold the plate and frame together, yet permitting of the free movement of the plate with respect to the frame.

q, is a cushion shown as comprising a coiled spring surrounding the tubular projection *e*, and interposed between the plate *m*, and frame *d*. Snugly fitting the chamber *r*, formed by the tubular projection of the frame and the flange of the plate which overlap, is a cushioned plunger or piston *s*, in which there is a receiving valve *s*, preferably smaller than the valve *g*, and adapted nor-

mally to rest upon the valve seat s^2 , the valve being retained from dislodgment from the plunger or piston by means of a suitable retaining pin. The valve g , is likewise retained from dislodgment by a similar pin. The plunger or piston as a whole is likewise retained in proper position by means of a pin t . As shown, this plunger or piston s , is provided with a somewhat contracted portion u , thus leaving a seat u^1 . Between this seat u^1 , and the pins o , upon the depending projection n , of the plate, is a cushion comprising a coiled spring v . By this arrangement vibrations imparted to the plate m , direct by the journal will obviously cause a similar direct vibration with respect to the plunger or piston s , whereby free distribution of lubricant will be imparted to the journal b , by reason of the valve s^1 , leaving its valve seat. From this description and as shown in the drawings it will be readily understood that the cushioned plunger is carried by and wholly retained within the sleeve n , of the journal plate m . The lubricator, as a whole, is adapted to be retained in proper position with respect to the journal and axle box by virtue of the device w . As shown, this device w , comprises a thin metallic strip having a somewhat curved end w^1 and a somewhat angular shelf-like member w^2 . There is also present a stop w^3 , and a spring-like catch w^4 , shown as being stamped from the strip. In practice, the device w , is inserted in the axle box as shown in Fig. 1, and the lubricator placed in proper position by passing the same over the spring catch w^4 , and causing the same to abut against the stop w^3 . The spring catch w^4 , will obviously move upward after the passage thereover of the lubricator and thus together with the stop w^3 , hold the lubricator in proper position. In this connection the ledge w^2 , prevents oil from splashing up and finding its way from the box through the axle box in the rear thereof.

What I claim as new is:

1. The combination in a car axle box of a journal, a bearing for the journal, a frame mounted in the bottom of the box and hav-

ing an upwardly extending sleeve, said frame being provided with a valve and valve seat, a cushioned plate in contact with the underside of the journal provided with a downwardly extending sleeve projecting within the sleeve of the frame, and a cushioned plunger mounted within and carried by the downwardly projecting sleeve, said plunger being provided with a valve and valve seat.

2. A guide for lubricators, comprising a comparatively thin, generally rectangular member provided with an angular extension forming a shelf at one of its ends and resilient means arranged centrally of the member for engaging a lubricator.

3. The combination in a car axle box of a journal, a bearing for the journal, a frame mounted in the bottom of the box, said frame having an upwardly extending sleeve and a receiving valve, means for retaining the valve in a vertical position during its movement, a cushioned journal plate in contact with the underside of the journal, said plate being provided with a downwardly projecting sleeve, and a cushioned plunger carried by and contained within said sleeve, said plunger being provided with a discharge valve, the last mentioned valve being smaller than the first mentioned valve.

4. The combination in a car axle box of a journal, a bearing for the journal, a frame mounted in the bottom of the box having an upwardly extending sleeve, said frame being provided with a valve and valve seat, means for retaining the valve in a vertical position in opening and closing, a journal plate having a rearwardly extending wiper in contact with the underside of the journal provided with a downwardly projecting sleeve, a plunger within the sleeve said plunger having a valve and valve seat, and a spring interposed between the piston and the lower portion of the sleeve.

In testimony whereof I have hereunto signed my name in the presence of witnesses.

GEORGE F. GODLEY.
